G. A. JANICKE.

TELEPHONE.

APPLICATION FILED OCT. 31, 1912.

1,142,173.

Patented June 8, 1915.

UNITED STATES PATENT OFFICE.

GUSTAVUS A. JANICKE, OF LOUISVILLE, KENTUCKY.

TELEPHONE.

1,142,173.

Specification of Letters Patent. Patented June 8, 1915.

Application filed October 31, 1912. Serial No. 728,890.

To all whom it may concern:

Be it known that I, GUSTAVUS A. JANICKE, a citizen of the United States, residing at Louisville, in the county of Jefferson and 5 State of Kentucky, have invented certain new and useful Improvements in Telephones; and I do declare the following to be a full, clear, and exact description of the invention, such as will enable others skilled in 10 the art to which it appertains to make and use the same.

This invention relates to improvements in telephones and more especially to an apparatus which may be used as a repeater or a 15 relay, which may be placed at desired points along the line and thereby maintain the maximum strength of the current and adapted to repeat with increased volume in either direction.

20 The primary object therefore of the invention is in the provision of an apparatus of the character described whereby a telephone message may be transmitted from one station to another or from a plurality of 25 stations.

A further object of the invention consists in constructing the apparatus in such a manner that the sound waves produced by the electrical impulses of the diaphragm or 30 armature of the receiver is automatically collected and distributed by the transmitter to which the local circuit is connected.

Primarily the invention consists of the 35 combined transmitter and receiver as previously referred to which are separated by an air tight chamber the diaphragms of which are in electrical and yielding contact in a manner herein described.

With these and other objects in view, the 40 invention consists of certain novel features of construction, and the combination and arrangement of parts as will be more fully described and claimed.

The drawing is a longitudinal section of 45 the complete invention.

In the illustrative embodiment of the invention 1 represents a receiver of conventional design and composed preferably of hard rubber or other insulating material and 50 constructed to properly and detachably receive the various parts of which the invention is composed.

Secured in the usual manner to the rear end of the receiver 1 are two binding posts

2 to which the main line wires are in electrical contact and leading from the same and in electrical contact therewith are wires 3 which are connected to the electromagnets 4 all of which are secured within said receiver 1 and snugly confined therein. 55

The poles 5 of the electromagnet are composed of soft metal and in binding contact with a permanent magnet 6 by binding screws 7 as clearly shown, whereby said magnet and poles are in electrical and magnetic 65 contact.

The receiver as constructed is flared outwardly and provided with external screw threads upon which is removably secured a ring or collar 8 having corresponding screw 70 threads and an annular flange 9 which is adapted for rigid contact with a diaphragm 10, whereby the latter is securely held in proper position in respect to the poles of the electromagnet but normally out of contact therewith. Secured to said ring or collar 8 in a mechanical manner is a cover or cap 11 and confined therein is a transmitter body 12 which is provided with an annular recess 13 which receives a diaphragm 14 and 75 disposed between said diaphragm and the plate 15 also confined in said body are carbon fillings or other insulating material 16. The diaphragms 10 and 14 within the air tight compartment 17 thus constructed are 80 connected by a wire 18 which forms an auxiliary means for taking up the vibrations between the diaphragm which wire is flexibly connected to said diaphragms, whereby the same are adapted to vibrate independently 85 of one another when the diaphragm 10 is attracted to and from the poles of the electromagnets. The main line wires 19 are connected to the binding posts 2 and the branch wires 20 which lead to a series of devices of 90 the character described and in electrical contact with binding posts 21, one of said posts being in electrical contact with the plate 15 and the other attached to the diaphragm 14, whereby the proper circuit is maintained under all conditions. 95

From the foregoing description taken in connection with the accompanying drawings, the construction and operation of the invention will be readily understood without requiring a more extended explanation. 105

Various changes in the form, proportion and the minor details of construction may be

resorted to without departing from the principle or sacrificing any of the advantages of this invention as defined and claimed.

Having thus described my invention, what I claim is:

- 5 In a device of the character set forth, the combination with a tubular receiver body closed at one extremity and having the other end thereof outwardly flared and externally threaded, a permanent magnet in said body, electromagnets connected to the extremities of said permanent magnet, means for connecting said electromagnets with an external circuit, a shoulder formed around the interior of said body contiguous to the flared end thereof, a diaphragm disposed upon said shoulder in-operative relation to the poles of said electromagnets, a collar having an internally threaded flange depending from its 10 edge, said flange adapted to engage the threaded portion of said body, said collar having therein an annular opening surrounded by a depending flange adapted to project within the open end of said receiver body and engage said diaphragm to fixedly 15 retain the latter; of a transmitter body hav-

ing therein an annular recess, an internal shoulder formed on the transmitter body adjacent the outer end of said recess, a cap incasing said transmitter body, said cap having an inwardly projecting flange adapted to co-operate with the shoulder on said transmitter body whereby to form an annular groove, the diaphragm having its edge disposed within said groove, a metallic plate 30 disposed at the inner end of said recess, carbon granules interposed between said plate and diaphragm, the latter co-acting with the first-mentioned diaphragm to form an air space between said receiver and transmitter, means to equalize the movement of the two diaphragms, and means whereby the last mentioned diaphragm and metallic plate may be connected to an exterior circuit.

In testimony whereof I have hereunto set my hand in presence of two subscribing witnesses.

GUSTAVUS A. JANICKE.

Witnesses:

DUDLEY T. WELCH,
OSCAR B. JANICKE.
